PRINTING PRESS

Hobart N. Durham, Munsey Park, Manhasset, N. Y., assignor to The Goss Printing Press Company, Chicago, Ill., a corporation of Illinois

Application May 9, 1935, Serial No. 20,533

21 Claims. (Cl. 270—68)

The present invention relates to printing presses and more particularly to a novel and improved rotary folding mechanism adapted for use with high speed newspaper presses.

5 Objects and advantages of the invention will be set forth in part hereinafter and in part will be obvious herefrom, or may be learned by practice with the invention, the same being realized and attained by means of the instrumentalities 10 and combinations pointed out in the appended claims.

The invention consists in the novel parts, construction, arrangements, combinations and improvements herein shown and described.

15 The accompanying drawing, referred to herein and constituting a part hereof, illustrates one embodiment of the invention, and together with the description, serves to explain the principles of the invention.

20 The single figure of the drawing is a diagrammatic sectional view of an illustrative folding mechanism in accordance with the present invention.

The present invention has for its object the 25 provision of a novel and improved high speed rotary folding mechanism which is particularly adapted for use with high speed rotary newspaper presses. A further object of the invention is the provision of a simplified rotary folding mechanism having fewer operating parts and which is less expensive in its construction than those now generally employed. Still another object of the invention is the provision of a high speed 30 rotary folding mechanism in which the tucking blade, heretofore almost universally used, is rendered unnecessary, and which mechanism may operate on webs or sheets.

In accordance with the illustrative embodiment 35 of the present invention, there is provided a folding cylinder and cooperating cutting cylinders between which the web or associated webs is cut into sheet lengths, and the folding cylinder is provided with means for taking the lead end of the web and holding it for a portion of a revolution 40 against the surface of the folding cylinder. Means are provided for releasing the holding means and for stopping the lead end of the associated webs while the body of the associated webs continues to feed in the direction of travel 45 of the cylinder. Other means are provided for holding the associated webs substantially to the shape of the folding cylinder throughout the major portion of the length of the sheets to be cut therefrom and except for a small distance 50 adjacent to a pair of folding-off rollers. These

rollers are driven at a peripheral speed slightly in excess of the peripheral speed of the folding cylinder, so that when the lead end of the webs or sheets is stopped, the body of the webs or sheets continues to move forward, buckles and the sheets are fed into the bite of the folding-off rollers which removes them from the cylinder and moves them toward suitable delivery mechanism. In order to facilitate buckling of the sheets air is introduced between the cylinder and the collected sheets at and adjacent to the proposed folding line, and in addition, the sheets are preferably creased mid-way of their length, that is, along the proposed fold line.

It will be understood that the foregoing general description and the following detailed description as well, are exemplary and explanatory of the invention but are not restrictive thereof.

Referring now in detail to the illustrative embodiment of the present invention, as shown in the accompanying drawing, there is provided a folding cylinder 10 substantially two sheet lengths in circumference, and a closely adjacent cutting cylinder 11 driven at the same peripheral speed as the folding cylinder and of an integral 20 number of sheet lengths in circumference. The longitudinally folded, and if desired slit, web or associated webs 12 are drawn downwardly by the drawing rolls 13 so that they are fed to the point of contact between the cylinders 10 and 11, 25 at substantially the same speed as the peripheral speed of these cylinders.

Cutting cylinder 11 is provided with a radially projecting blade 15 of conventional construction 30 adapted to seat within the female cutting blocks 16 mounted on folding cylinder 10 and which are spaced a sheet length apart as measured on the circumference of the folding cylinder 10. Means are preferably provided for introducing or maintaining air between cylinder 10 and the sheets 35 along and adjacent to the proposed fold line, and said means are likewise also utilized for creasing the sheets along the proposed fold line. Accordingly a blade 14' is made to project slightly from the periphery of cylinder 10 along the proposed 40 fold line, and would act by itself to hold the sheets slightly away from the cylinder and admit the air along either side thereof beneath the sheets. The mechanism is also adapted to crease the sheet along the proposed fold line, and accordingly cylinder 11 is also provided with a creasing 45 groove 14 to cooperate with creasing blade 14' fixed to the cylinder 10. Groove 14 and blade 14' are spaced from the blade 15 and block 16 one-half sheet length.

The sheet taking means on the folding cylinder 10, for taking the leading end of the web or associated webs, comprise axially aligned series of impaling pins 18 carried by arms 19 mounted on pin shafts 20 which are rotatably journaled in the folding cylinder 10. At one end of each shaft 20 is provided an arm 21 carrying cam roller 22 which runs in the cam track 23 of a stationary pin actuating cam 24, fixed to and angularly adjustable on the folder frame so that the timing of the pins may be varied.

Means are provided for conforming the paper to the cylindrical shape of the folding cylinders 10, and as embodied, comprise series of relatively narrow spaced-apart sheet guides having curved inner faces which are positioned concentrically with respect to the folding cylinder 10. Sheet guides 30 and 31 are mounted on a supporting shaft 32 while sheet guides 33, 34, and 34' are mounted on their supporting shafts 35 and 35'. These guides are preferably held in the position shown in Figure 1 during the operation of the press by set screws or other suitable means. Guides 33, 34, and 34' extend from a point closely adjacent to the point of cutting and between the folding cylinder 10 and cutting cylinder 11 to a point above folding roller 36, and folding roller 36 is provided with circumferential grooves to receive the ends of guides 34'. The ends of guides 31 are similarly received within circumferential grooves on the folding roller 37.

Folding rollers 36 and 37 are rotatably mounted closely adjacent to the lower part of the folding cylinder 10 and are yieldingly mounted and resiliently urged towards each other so as to tightly grip and feed the folded sheets as the sheets are folded off from the cylinder by these rollers. Rollers 36 and 37 are driven at a peripheral speed slightly in excess of that of the folding cylinder 10, and roller 36 is driven in the opposite angular direction to cylinder 10, while roller 37 is driven in the same angular direction as folding cylinder 10. At the point of contact between rollers 36 and 37 the rollers are travelling in the same peripheral direction.

Means are provided for stopping the lead end of the sheet or associated sheets at a point beyond the folding rollers 36 and 37 and almost a half sheet length from these rollers. For this purpose, stop 41 may be mounted at the upper ends of sheet guides 30 and is directed inwardly towards the cylinder surface and closely adjacent thereto, being spaced however to permit passage of the creasing blades 14.

Means are also provided for lifting the associated sheets from the impaling pins 18 and for this purpose small bifurcated fingers 38 overlie the pins 18, are pivoted on the cylinder and connected to pin arms 19 by links 39. As the pins 18 are retracted, the fingers 38 are lifted projecting the lead end of the sheets against stop 41.

If desired, means may be provided beyond the cutting cylinder 11 for forwarding the sheets after the lead end of the sheets has been released by the impaling pins 18, and for this purpose axially aligned sections of a feed roller 42 are rotatably mounted and yieldingly pressed towards the surface of the folding cylinder 10, rollers 42 being positioned between the cutting cylinder 11 and the folding roller 36. The spaced guides 34 may be positioned between the several sections of the feed roller 42. Roller 42 is also recessed to cooperate with creasing blades 14', is preferably a half page in circumference and is driven at paper speed from the cylinder 10.

In the operation of the illustrative embodiment of the invention, the associated webs 12 have been printed, associated, longitudinally folded or slit and are fed towards the point of cutting by means of the drawing rollers 13, the speed of the webs 12 being substantially the same as the peripheral speed of the cylinders 10 and 11. The associated webs 12 are cut by cutting knife 15 and the lead end of the web is impaled by the pins 18 immediately above the point of cutting. As the folding cylinder 10 continues to rotate, the lead end of the web is moved in a clockwise direction, the sheets are creased along the line where they are to be folded, and when the lead end of the web is immediately below the stop 41, cam 23 withdraws the impaling pins 18, thereby freeing the lead end of the associated webs 12. The portion of the webs between the stop 41 and the cutting cylinders 11 continues to travel by reason of the inertia of the paper, and the continued feeding of the webs by the cutting cylinder 11 by its pressing the webs against the folding cylinder 10. During this time, the webs are confined against the surface of the folding cylinder and held substantially concentric therewith by means of the inner curved surfaces of the spaced-apart guides 30, 31, 33, and 34.

When the lead end of the web comes to rest against the stop 41, the associated webs are circumferentially compressed, that is, lengthwise of the webs, and the webs being already creased and in a curved form, tend to move radially of the folding cylinder 10 under the influence of the longitudinal inertia compression of the webs as well as due to the centrifugal force developed by the mass and angular movement of the webs. This action causes the sheet to buckle exactly at its mid-portion and transversely of the web, as shown at 45, this buckle occurring immediately above the bite of the folding rollers 36 and 37. As the buckle 45 enlarges, the outer surface of the webs engages the surface of folding rollers 36 and 37, causing the buckle to be fed between the rollers, thereby folding and creasing the sheets. By properly positioning the stop 41, substantially in the position shown in Figure 1, the line of transverse fold can be positioned accurately midway between the ends of the sheet. Approximately at the time the line of fold 45 is firmly gripped between the folding rollers 36 and 37, the webs are cut by the blade 15, thereby severing the folded sheets from the web and forming a new lead end of the web which is impaled by the next set of impaling pins 18. Continued rotation of the folding rollers 36 and 37 causes the forward half of the sheet to be reverse fed while the trailing half of the sheet continues to feed in the same direction, and the folded group of associated sheets is fed from the folding cylinder 10 between the folding rollers 36 and 37 and is thereby conveyed to suitable delivery mechanism (not shown).

The invention in its broader aspects is not limited to the specific mechanism shown and described but departures may be made therefrom within the scope of the accompanying claims without departing from the principles of the invention and without sacrificing its chief advantages.

What I claim is:—

1. A high speed rotary folding mechanism including in combination a sheet carrying cylinder, sheet taking means mounted on said cylinder, a pair of folding-off rollers, and means for buckling a plurality of sheets from said cylinder in-

- cluding a positive stop engaging the forward ends of the sheets.
2. A high speed rotary folding mechanism including in combination means for cutting sheets from a group of associated webs, a sheet carrying cylinder, a pair of folding-off rollers, sheet confining means adjacent to said cylinder, continuously acting means for forwarding said sheets between said cylinder and confining means, and means projecting into the pathway of said sheets, beyond the folding-off rollers to stop the angular movements of said sheets.
3. A high speed rotary folding mechanism including in combination means for cutting sheets from webs, a sheet carrying cylinder, a pair of folding-off rollers, sheet confining means adjacent to said cylinder, continuously acting means for forwarding sheets between said cylinder and confining means and a stop projecting into the pathway of said sheets to stop the angular advance thereof; said stops being positioned beyond said folding-off rollers.
4. A high speed rotary folding mechanism including in combination means for cutting a sheet from a web, a sheet carrying cylinder, a pair of folding-off rollers, sheet confining means adjacent to said cylinder, continuously acting means for forwarding a sheet on said cylinder, and a stop projecting into the path of the sheet beyond the folding-off rollers to stop the angular advance thereof.
5. A high speed rotary folding mechanism including in combination a sheet carrying cylinder, a pair of folding-off rollers, sheet confining means adjacent to said cylinder, a cutting cylinder cooperating with the folding cylinder, a roller pressing the sheet against the cylinder to forward the sheet and a stop beyond the folding rollers for arresting angular advance of a sheet.
6. A high speed rotary folding mechanism including in combination a sheet carrying cylinder, a pair of folding-off rollers, sheet confining means adjacent to said cylinder, a cutting cylinder cooperating with the folding cylinder, sheet taking means on said carrying cylinder, a roller pressing the sheet against the cylinder to forward the sheet and a stop at the end of the confining means for arresting angular advance of a sheet.
7. A rotary buckling folder including in combination a folding cylinder, sheet guides concentric therewith, folding-off rollers, a cutting cylinder, sheet taking means on said folding cylinder, actuating means therefor to release the lead end of sheets prior to cutting at their rear end, and a sheet stop positioned less than a semi-circumference of said cutting cylinder from the sheet cutting means.
8. A high speed rotary folding mechanism including in combination a sheet carrying cylinder, sheet taking means mounted on said cylinder, means for creasing a sheet on said cylinder, a pair of fold-off rollers and means for buckling a sheet from said cylinder and folding it along the crease.
9. A rotary buckling folder including in combination a folding cylinder, sheet guides concentric therewith, folding-off rollers, a cutting cylinder, sheet taking means on the folding cylinder, a sheet creasing blade on the folding cylinder, and a sheet stop for buckling a sheet along the crease and between the rollers.
10. A rotary folder including in combination a folding cylinder, sheet guides concentric therewith, fold-off rollers, sheet forwarding means, a stop against which the sheets are moved and

means for projecting the sheets into the path of said stop.

11. A high speed rotary folding mechanism including in combination a sheet carrying cylinder, sheet taking means mounted on said cylinder, a pair of folding-off rollers, means for feeding sheets to said cylinder and means separate from folding-off rollers for stopping angular advance of the portion of the sheets in advance of the folding rollers and means for continuing the movement of that portion of the sheets on the other side of the folding rollers.

12. A high speed rotary folding mechanism including in combination a sheet carrying cylinder, sheet taking means mounted on said cylinder, a pair of folding-off rollers, means for feeding sheets to said cylinder and means separate from said sheet carrying cylinder and folding-off rollers for stopping angular advance of the portion of the sheets in advance of the folding rollers and means for continuing the movement of that portion of the sheets on the other side of the folding rollers.

13. A rotary folding mechanism including in combination a sheet carrying cylinder, sheet taking means thereon, a pair of folding-off rollers, means for stopping the front half of a sheet or sheets on said cylinder while the sheets are free from said folding-off rollers to buckle the center of the sheet and bring the buckle into the bite of the folding-off rollers.

14. A rotary folding mechanism including in combination a sheet collecting cylinder, sheet collecting means thereon, a pair of folding-off rollers, and means for engaging and stopping the front half of all the collected sheets to buckle the center of the group into the bite of the folding-off rollers.

15. A rotary folding mechanism including in combination a sheet collecting cylinder, sheet collecting means thereon, a pair of folding-off rollers, and a stop engaging the front end of all the collected sheets to buckle the center of the group into the bite of the folding-off rollers.

16. A rotary folding mechanism including in combination a sheet carrying cylinder, folding-off rollers, sheet confining means spaced from and concentric with said cylinder and extending from said folding-off rollers toward the lead end of a sheet on the cylinder and means for buckling the center part of the sheet into the bite of said folding rollers including means for stopping the lead half of said sheet.

17. A rotary folding mechanism including in combination a sheet carrying cylinder, folding-off rollers and means for buckling the central part of said sheet into the bite of the folding-off rollers comprising a stop for the front half of the sheet and means for confining the sheet spaced from said cylinder between the folding rollers and the head of the sheet.

18. A rotary folding mechanism including in combination two coacting cylinders, a web supply, impaling pins on one of said cylinders, cooperating sheet cutting devices on said cylinders, means for creasing sheets medianly and transversely, a pair of folding-off rollers, sheet confining means located in advance of said folding-off rollers, and means for stopping the forward half of sheets upon the cylinder to buckle the crease into the bite of the folding rollers.

19. A high speed rotary folding mechanism including in combination a sheet carrying cylinder, sheet taking means mounted on said cylinder, means for maintaining air between said cylinder

and a sheet thereon across a limited median part of the sheet, a pair of folding-off rollers, and means for buckling a plurality of sheets from said cylinder.

5 20. A rotary folding mechanism including in combination a sheet carrying cylinder, sheet taking means thereon, a pair of folding-off rollers, means for stopping the front half of a sheet or sheets on said cylinder while the sheets are free 10 from said folding-off rollers to buckle the center of the sheet and bring the buckle into the bite

of the folding-off rollers, and means for maintaining air between the cylinder and sheet at said buckling and folding-off locus.

21. In a rotary buckling folder, a folding cylinder, folding-off rollers, a curved stationary sheet guide concentric with said folding cylinder, a roller pressing the sheet against the cylinder to forward the sheet and a stop projecting into the space between the guide and cylinder to arrest angular advance of a sheet. 5

HOBART N. DURHAM. 10
